CERTAIN PYRIDYLMETHYL GUANIDINE
DERIVATIVES

William F. Minor, Fayetteville, N.Y., assignor to Bristol-
Myers Company, New York, N.Y., a corporation of
Delaware
No Drawing. Filed Mar. 18, 1965, Ser. No. 440,948
12 Claims. (Cl. 260—296)

ABSTRACT OF THE DISCLOSURE

1 - (lower)-alkyl-1-(2'-pyridylmethyl)guanidines, their N-alkylated derivatives and the corresponding compounds containing a methyl group at the 6-position of the pyridine ring are anti-depressant agents which counteract psychic depression without stimulating motor activity or appearing to stimulate the central nervous system.

Background of the invention

(1) *Field of the invention.*—This invention relates to chemical compounds acting as antidepressants which are useful in the treatment of psychic depression in man.

(2) *Description of the prior art.*—The compounds of the present invention represent a new family of anti-depressant agents. Heretofore compounds of this general chemical structure have only been associated with anti-hypertensive activity.

Summary of the invention

The 1-(lower)-alkyl-1-(2'-pyridylmethyl)guanidines of the present invention are compounds having the formula

in which R' is a member selected from the group consisting of hydrogen and methyl, R2 represents (lower) alkyl and R3, R4 and R5 each represent a member selected

A.

from the group consisting of hydrogen and (lower)alkyl; and the nontoxic pharmaceutically acceptable acid addition salts thereof.

This invention relates to a novel series of nontoxic antidepressant agents which counteract psychic depression without stimulating motor activity or appearing to stimulate the central nervous system and, more particularly to 1-(lower)-alkyl-1-(2'-pyridylmethyl)guanidines and their N-alkylated derivatives and the corresponding compounds containing a methyl group at the 6-position of the pyridine ring and their non-toxic, pharmaceutically acceptable acid addition salts.

It was the object of the present invention to provide novel nontoxic antidepressant agents whose use would not be restricted by their exhibition of other pharmacological activity, e.g. hypotensive action, inhibition of monoamine oxidase. Thus, the hypotensive or the diuretic action frequently exhibited by previously investigated guanidines is highly undesirable in an antidepressant agent.

The object of the present invention has been achieved

2

by the provision, according to the present invention, of bases of the formula

in which R1 is hydrogen or methyl, R2 is (lower)alkyl and preferably methyl and R3, R4 and R5 each represent hydrogen or (lower)alkyl; and the nontoxic, pharmaceutically acceptable acid addition salts thereof.

A preferred embodiment of the present invention consists of the salt and free base forms of the compounds of the formula

wherein R represents (lower)alkyl.

Another preferred series of compounds of the present invention is that of the compounds of the formula

wherein R represents (lower)alkyl.

The compounds of the present invention are best prepared from commercially available 2-picolylmethylamine (also named 2-methylaminomethylpyridine) or 6-methyl-2-picolylmethylamine (also named 6-methyl-2-methylaminomethylpyridine) (Aldrich Chemical Co.) or a 2-(lower)alkylaminomethylpyridine or a 6-methyl-2-(lower)alkylaminomethylpyridine by reacting such amine with a 2-methyl-2-thiopseudourea or a cyanamide or a 3,5-dimethyl-1-guanylpyrazole (also called a 3,5-dimethylpyrazole-1-carboxamidine) as illustrated by the following equations:

wherein R1, R2, R3, R4 and R5 have the meanings set out above. The products are recovered as the free base or acid addition salt depending upon the procedure used for their isolation.

The use of method A includes the corresponding substituted 2-methyl-2-thiopseudoureas (also called S-methyl-isothioureas) prepared by the reaction of a (lower)alkyl iodide or a di(lower)alkyl sulfate with, for example, N-

methylthiourea, N-n-butylthiourea, N,N'-diethylthiourea, N,N,N'-trimethylthiourea. In a useful procedure equimolar amounts of the amine and 2-methyl-2-thiopseudourethane sulfate or hydriodide in water or ethanol are heated under reflux for several hours or allowed to stand at room temperature overnight. The higher temperatures are preferred. The product is recovered by removal of the solvent in vacuo. The necessary thiopseudoureas (also called isothioureas) can be made as follows

wherein R³, R⁴ and R⁵ are each hydrogen or (lower)alkyl. (See Organic Syntheses III, 363 and British Patent 973, 882.) These S-methylpseudothioureas may be replaced by O-methylpseudoureas.

The use of method B includes substituted cyanamides which are prepared as reported in the literature and especially by the reaction in equivalent amounts in a solvent such as diethyl ether of cyanogen chloride or cyanogen bromide with an amine of the formula

wherein R⁴ and R⁵ are each hydrogen or (lower)alkyl. Exemplary conditions include refluxing equimolar amounts of the amine and the cyanamide in water, as for six hours with recovery as above.

In using method C the reaction may be carried out by fusing the reactants or by heating them in the presence of a diluent such as an alkanol, e.g. ethanol, and advantageously with the exclusion of carbon dioxide by performing the reaction in an inert atmosphere, e.g. under nitrogen.

The 2-(lower)alkylaminomethylpyridines used in the above reactions are prepared, for example, by the following process:

wherein R¹ represents hydrogen or methyl and R² represents hydrogen or (lower)alkyl.

The term "(lower)alkyl" as used herein refers to straight and branched chain saturated monovalent aliphatic hydrocarbon radicals having from one to ten carbon atoms inclusive, e.g. methyl, ethyl, propyl, isopropyl, butyl, normal and secondary and tertiary butyl, amyl, decyl, etc.

Included within the present invention are the acid addi-

tion salts prepared by reaction of these basic compounds with organic and inorganic acids such as hydrochloric acid, hydrobromic acid, sulfuric acid, phosphoric acid, acetic acid, maleic acid, tartaric acid, citric acid, sulfamic acid, glycolic acid, succinic acid, ascorbic acid and the like. Mono- or poly-salts may be formed.

The new guanidine compounds may be obtained in the form of the free compounds, or as the salts thereof. A salt may be converted into the free compound in the customary way, for example, by treatment with a strong alkaline reagent, such as aqueous alkali metal hydroxide, e.g. lithium hydroxide, sodium hydroxide, potassium hydroxide and the like, or a strong quaternary ammonium anion (hydroxy ion) exchange resin and the like. A free base may be transformed into its therapeutically useful acid addition salts by reacting the latter with an appropriate inorganic or organic acid, such as one of those outlined hereinabove; such reaction may be carried out advantageously in a solvent, such as, for example, a lower alkanol, e.g. methanol, ethanol, propanol, isopropanol and the like, an ether, e.g. diethylether, p-dioxane and the like, a lower alkyl lower alcanoate, e.g. ethyl acetate and the like, or a mixture of such solvents, and isolating the desired salt. Salts of the polybasic compounds of this invention may be obtained, in which not all of the salt-forming basic groups participate in the salt formation. Such salts may be treated with an acid in order to form compounds in which all or a greater number of the basic groups take part in the salt formation.

For use as antidepressant agents, these compounds are associated with a significant amount of a pharmaceutically acceptable carrier which may be either a solid material or a liquid. The compositions may take the form of tablets, effervescent tablets, powder, granules, capsules (both hard and soft shell capsules), or suspensions in edible oils, or other dosage forms which are particularly useful for oral ingestion. Liquid diluents are employed in sterile conditions for parenteral use, that is by intramuscular, intravenous and intraperitoneal injection. Such a medium may be a sterile solvent or suspending agent such as water or an injectable oil. The compositions may take the form of active material admixed with solid diluents and/or tabling adjuvants such as corn starch, lactose, talc, stearic acid, magnesium stearate, gums or the like. Any of the encapsulating or tabling materials used in pharmaceutical practice may be employed where there is no incompatibility with the compounds. The materials may be tabbed with or without adjuvants. Alternatively, the compounds may be placed in the usual capsule or resorbable material such as the usual gelatin capsule and administered in that form. In yet another embodiment, the compounds may be put up as a powder and so employed, as by nasal inhalation, or the compounds may be prepared in the form of a palatable suspension in which the compounds are not soluble. Suspensions may be given orally as made or may be encapsulated. Ointments and lotions are useful topically; use for topical therapy is made of nose drops, troches and suppositories. The compounds of the present invention are particularly useful when given by the oral, intramuscular, or intravenous routes; a useful dosage range in man is about 10-1000 mgms. per dose. Dosages are given about one to six times per day, depending on the patient, the infection, the route of administration and the like.

The percentage of the active ingredients in these compositions may be varied. It is necessary that the active ingredients constitute a proportion such that a suitable dosage will be obtained. Obviously, several unit dosage forms may be administered at about the same time. Although it is found, particularly on intravenous injection, that a percentage of less than 0.10 percent of the compound is effective, it is preferable to use not less than 0.10 percent of the compounds. Activity increases with the concentration of the compound. The percentage of active agent may be 10 percent, or 25 percent, or even a higher proportion of the substance administered. For

example, tablets may be prepared with a minor proportion of diluent and a major proportion of active material. Tablets containing from about 10 to 1000 mgms. of the compound are particularly useful. The solid pharmaceutical carrier used may be an envelope enclosing pure compound in a gelatin capsule.

The following examples will illustrate the present invention without limiting it thereto.

EXAMPLE I

1-methyl-1-(2-pyridylethyl)guanidine sulfate.—To a warm solution of 13.9 g. (0.05 mole) of 2-methyl-2-thiopseudourea sulfate in 40 mil. water was added 12.2 g. (0.10 mole) of 2-picollylmethylamine (Aldrich Chemical Co.). Brief warming caused a vigorous reaction with evolution of methyl mercaptan. After being heated for three hours on the steam bath the solution was cooled and the crystalline product, 1-methyl-1-(2-pyridylmethyl) guanidine sulfate, was collected and recrystallized from 50% ethanol; yield 4.3 g., M.P. 267.5–268° C. (dec.).

Analysis.—Calc'd for $(C_8H_{12}N_4)_2 \cdot H_2SO_4 \cdot H_2O$: C, 43.23; H, 6.35; N, 25.21. Found: C, 43.45; H, 6.32; N, 25.50.

This compound exhibited an oral LD₅₀ in mice of about 700 mgm./kg. and at doses of 10 mgm./kg. (and even as low as 2 mgm./kg.) p.o. in the mouse given prior to treatment with 5 mgm./kg. reserpine caused the mice to behave normally and prevented the usual sedative effect of reserpine. This is a marked contrast to the results of pretreatment with monoamine oxidase inhibitors before reserpine dosage as in that instance the mice exhibit great motor stimulation and indeed become so hyperactive that death usually results. Thus this compound exhibits marked antidepressant activity without the undesirable motor stimulation of the usual monoamine oxidase inhibitors.

EXAMPLE 2

Substitution in the procedure of Example 1 for the 2-methyl-2-thiopseudourea sulfate used therein of an equimolar weight of the substituted 2-methyl-2-thiopseudoureas of the formulae:

respectively, produces the products of the formulae

and

respectively, as their sulfate salts.

EXAMPLE 3

Substitution in the procedure of Example 1 for the 2-picollylmethylamine used therein of an equimolar weight of 2-ethylaminomethylpyridine and 2-n-propylaminomethylpyridine, respectively, produces the compounds of the formulae

and

respectively.

EXAMPLE 4

Repetition of the procedures of Example 2 with the replacement of the 2-picollylmethylamine used therein with an equimolar weight of 6-methyl-2-picollylmethylamine produces the compounds of the following formulae:

and

70

75 respectively, as their sulfate salts.

7
EXAMPLE 5*1-methyl-1-(6'-methyl-2'-pyridylmethyl)guanidine hemisulfate monohydrate.*—To a solution of 13.6 g. (0.10 mole) of 6-methyl-2-picolylmethylamine (Aldrich) in 40 ml. water there was added 14.0 g. (0.05 mole) of 2-methyl-2-thiopseudourea sulfate (Eastman Kodak Co.). The mixture was heated to reflux and then refluxed for 6.5 hours. The evolution of methyl mercaptan became 15 vigorous at about 80° C. The mixture was then allowed to stand overnight at 25° C. Upon cooling in ice crystalline 1-methyl-1-(6'-methyl-2'-pyridylmethyl)guanidine hemisulfate separated and was collected by filtration, recrystallized from aqueous acetone dried in vacuo over 20 P_2O_5 at 25° C. and found to weigh 3.4 g., M.P. 243-244.5° C. (dec.).

Analysis.—Calc'd for $C_{18}H_{30}N_8O_4S \cdot H_2O$: C, 45.75; H, 6.83; N, 23.71. Found: C, 45.75; H, 6.68; N, 23.50.

This compound at doses of 20 mgm./kg. (and even as low as 10 mgm./kg.) p.o. in the mouse given prior to treatment with 5 mgm./kg. reserpine caused the mice to behave normally and prevented the usual sedative effect of reserpine. This is a marked contrast to the results of pre-treatment with monoamine oxidase inhibitors before reserpine dosage as in that instance the mice exhibit great motor stimulation and indeed become so hyperactive that death usually results. Thus this compound exhibits marked antidepressant activity without the undesirable motor stimulation of the usual monoamine oxidase inhibitors.

The new guanidine compounds of the present invention also form quaternary ammonium compounds, particularly those with lower alkyl halides, e.g. methyl, ethyl, n-propyl or isopropyl chloride, bromide or iodide and the like, di-lower alkyl-sulfates, e.g. dimethyl sulfate, diethyl sulfate and the like, lower alkyl lower alkane sulfonates, e.g. methyl or ethyl methane or ethane sulfonate, or lower alkyl monocyclic carbocyclic aryl sulfonates, e.g. methyl p-toluenesulfonate, and the like, as well as the corresponding quaternary ammonium hydroxides and the salts, 45 which may be formed from the quaternary ammonium hydroxides by the reaction with inorganic acids other than the hydrohalic acids or with organic acids, such as those outlined above for the preparation of the acid addition salts.

The quaternary ammonium compounds may be obtained by reacting a free base with a lower alkyl halide, e.g. methyl, ethyl, n-propyl, isopropyl chloride, bromide or iodide and the like, a di-lower alkyl-sulfate, e.g. dimethyl sulfate, diethyl sulfate and the like, a lower alkyl lower alkane sulfonate, e.g. methyl or ethyl methane or ethane sulfonate and the like, or a lower alkyl monocyclic carbocyclic aryl sulfonate, e.g. methyl p-toluenesulfonate and the like. The quaternizing reaction may be performed in the presence of a solvent, such as, for example, a lower alkanol, e.g. methanol, ethanol, propanol, isopropanol, tertiary butanol and the like, a lower alkanone, e.g. acetone, methyl ethyl ketone and the like, or an organic acid amide, e.g. formamide, N,N-dimethylformamide and the like. The resulting quaternary ammonium compounds are effective antiseptic and germicidal agents.

While in the foregoing specification various embodiments of this invention have been set forth in specific detail and elaborated for the purpose of illustration, it will be apparent to those skilled in the art that this invention is susceptible to other embodiments and that many of the details can be varied widely without departing from the basic concept and the spirit and scope of the invention.

I claim:

1. A member selected from the group consisting of bases of the formula

in which R^1 is a member selected from the group consisting of hydrogen and methyl, R^2 represents (lower)alkyl and R^3 , R^4 and R^5 each represent a member selected from the group consisting of hydrogen and (lower)alkyl; and the nontoxic, pharmaceutically acceptable acid addition salts thereof.

2. The compounds of the formula

wherein R represents (lower)alkyl.

3. The compounds of the formula

wherein R represents (lower)alkyl.

4. The compounds of the formula

in which each of R^1 and R^2 is (lower)alkyl.

5. The compounds of the formula

in which R^1 , R^2 and R^3 each represent (lower)alkyl.

6. The compounds of the formula

wherein R^1 and R^2 each represent (lower)alkyl.

7. The compound of the formula

8. The compound of the formula

9. The compound of the formula

10. The compound of the formula

11. The compound of the formula

12. The compound of the formula
